DESIGN FOR AN EXPANSIBLE LINK CHAIN FOR A BRACELET OR THE LIKE

Joseph M. Bender, Manhasset, N. Y., assignor to
Jacoby-Bender, Inc., New York, N. Y., a corporation of New York

Original application March 2, 1949, Serial No.
1,174. Divided and this application May 25,
1949, Serial No. 2,881

Term of patent 7 years

(Cl. D45—4)

To all whom it may concern:

Be it known that I, Joseph M. Bender, a citizen of the United States and a resident of Manhasset, county of Nassau, and State of New York, have invented a new, original, and ornamental Design for an Expansible Link Chain for a Bracelet or the Like, of which the following is a specification, reference being had to the accompanying drawing forming a part thereof.

This application is a division of application, Serial No. D. 1,174, filed March 2, 1949.

Fig. 1 is a top view of the chain in contracted condition showing my new design;

Fig. 2 is a side elevational view of the chain, the conventional bottom links being shown in broken lines;

Fig. 3 is a top view similar to Fig. 1 but showing the chain in partially expanded condition, portions of the conventional bottom links being visible between the top links;

Fig. 4 is an enlarged end elevational view of one of the top links taken from the right side of Fig. 1; and

Fig. 5 is an enlarged end elevational view of the top link of Fig. 4 but taken from the left side of Fig. 1.

I claim:

The ornamental design for an expansible link chain for a bracelet or the like, as shown.

JOSEPH M. BENDER.
